COMMUNICATION AND GUIDING SYSTEM

Edmond M. Deloraine, New York, N. Y., and Paul R. Adams, Cranford, N. J., assignors to Federal Telephone and Radio Corporation, New York, N. Y., a corporation of Delaware

Application May 5, 1944, Serial No. 534,284

37 Claims. (Cl. 250—11)

1

This invention relates to communication and guiding systems and more particularly to a system for communicating with a moving craft or other mobile communication unit and for guiding a craft or unit along a particular route.

Systems have been previously proposed for simultaneously guiding a craft along a given route and communicating with the craft from the beacon or guiding station. The systems of beacons for guiding crafts along a given course may comprise a series of radio beacons overlapping in space at points along the course with provisions, such as marker beacons, intermediate the radiation patterns of the separate beacons in the region of the overlapping patterns warning when to change over for reception from a new beacon system. In one prior art arrangement, there is provided a system in which the receiver on the craft is tuned in response to a change of frequency from one beacon to another so that the indicator will switch over without special attention of the pilot. However, in this type of beacon system, no provision is made to cause the craft indicator to change its reception condition from one beacon to another at substantially the same point regardless of the direction of travel. Because of the inherent bias or sensitivity level needed to effect the control for changing the receiver tuning, this type of proposed beacon arrangement will cause the craft receiver to shift its reception condition at different points along the course depending on the direction of travel of the craft.

It is an object of our invention to provide a radio guiding beacon system in which a receiver carried by a craft following the beacon course from one beacon radiation pattern to another automatically changes its reception condition without special attention of the pilot and in which the change-over from reception of energy from one beacon to the other will take place at substantially the same point, regardless of the direction of travel along the beacon path.

It is a further object of our invention to provide a radio beacon system operative in combination with a radio craft receiver which will provide on the craft a uniform directional indication when passing from one beacon to another and in which the receiver is made to be selectively responsive to the separate beacons without special attention from the pilot and will change in selective response along the course at substantially the same point, regardless of the direction of travel of the craft.

It is contemplated that, along a given course

2

there may be a plurality of different craft travelling and it is, therefore, desirable to be able to communicate selectively with the different craft from a central station at any point along the beacon path. In a copending application of E. M. Deloraine, Serial No. 531,851, filed April 20, 1944, entitled "Repeater link system," is disclosed a repeater system for multiplex communication between two remote points by way of a plurality of directive repeaters together with the provision of arrangements for broadcasting or directive transmitting certain of the channels from each of the towers so that craft travelling along a line within range of these towers may communicate selectively with a base station or with each other.

It is a further object of this invention to provide a combined multiplex communication system of the general type disclosed in the aforementioned patent application, in combination with a beacon guiding system for guiding craft along a path defined by the line of radio towers.

It is a further object of our invention to provide a receiving circuit for use on a craft which will selectively receive multiplex communication channels and simultaneously receive beacon indicating signals.

It is a still further object of our invention to provide a combination communication system and beacon system in which a craft may follow along a line of towers provided with radio beacon radiators operating at alternately different radio frequencies and in which there is provided aboard each craft means for simultaneously receiving communication signals and guiding beacon signals and for automatically rendering the receiver operative selectively to the energy radiated from the alternate towers.

It is a still further object of our invention to provide, in a system as outlined above, means for assuring that the receiving equipment on board the craft changes from one alternate signal to the other substantially at the same point, regardless of direction of travel of the craft.

It is a still further object of our invention, to provide a system for communication with a craft and a guiding beacon therefore, in which communication and guiding equipment is arranged at spaced points along a course to be followed by a craft, and in which the equipment is rendered operative in response to signals from the craft in the vicinity of one of the stations, or to special control signals from a separate control station.

In accordance with a feature of our invention we may provide a multiplex communication sys-

tem in which a plurality of channels are transmitted from a single terminal station over a plurality of successive towers. At each of the towers, or at selected ones of the towers, are arranged radio beacons so aligned that energy from said beacons will slightly overlap the energy radiated from each succeeding beacon. Preferably the energy from successive towers is radiated at slightly different frequencies to avoid danger of duplicate reception. In the simplest form only two different frequencies alternate along the course. However, more frequencies may be used if desired, the frequency distributions to the different towers preferably being repeated successively along the course. Also, at each of the towers or at selected ones of the towers are branched off one or more communicating channels for broadcasting to the craft travelling along the course. The craft travelling along the course are each provided with receiving equipment for simultaneously receiving the branched off channel signals as well as the guiding beacon signals and for segregating these signals to provide separate indications. Also, on the craft is provided some means responsive to the received energy for rendering the receiving circuit responsive only to one of the successive frequencies.

In order that the switching may take place when the craft is in substantially the same area, regardless of the direction of travel of the craft, a separate marker beacon is provided adjacent the beginning of one of the beacon courses in the region of overlap of the two adjacent beacons. This marker beacon preferably transmits a relatively narrow fan shaped beam of energy upwardly, the energy being characterized by the same frequency as the beacon whose radiation pattern overlaps the pattern of the next necessary beacon. Thus, in one direction of travel, the response of the craft receiver will be changed immediately after this marker beacon is passed due to the energy received from the beacon. In the other direction of travel, energy from the marker beacon will serve to switch the receiver to respond to energy from the next radio beacon. Accordingly, the switching over of the craft of these alternate frequencies will occur in substantially the same area.

Furthermore, the craft is preferably provided with other communication equipment permitting transmission of signals from the craft to the towers along the course for communication with the base station or for communication between separate craft travelling along the course.

In the preferred form, the multiplex communication channels will each consist of a series of pulses separated properly in time so that they will interleave one with another. These pulses may be modulated in any suitable manner to provide pulse amplitude modulation or time displacement modulation or any other desired type of modulation. The particular type of modulation circuit used is not a feature of the present invention.

Likewise, the communication between the tower and the plane and the signals sent over the communication system may be of any desired form. Preferably, however, the beacon signals are of a relatively low frequency, for example, the normal 90-150 cycle tone frequencies or the known form of A-N keyed signals. The communication channels are preferably modulated pulse channels which may be readily separated from the guiding signals in the aircraft receiver by means of a clipper device so that segregation of the two

channels may be accomplished without heavy and complicated equipment.

According to a further feature of our invention, the successive towers and beacons are normally inoperative to broadcast to the craft or to transmit beacon guiding signals and at each tower or station is provided means responsive to signals from a craft in the vicinity thereof to transmit beacon signals, and/or to broadcast communication signals. Alternately, special signals from the base station may be transmitted to the towers for the purpose of rendering the beacon and/or broadcast communication operative. Both these selective systems may be incorporated in a common system, if desired.

While the system of our invention is particularly useful for the guiding of aircraft, it is not to be considered as limited thereto. The beacon may be used for guiding and/or establishing communication with any type of mobile unit in the vicinity of the system.

A better understanding of our invention and the objects and features may be had from the particular description of certain embodiments thereof, made with reference to the accompanying drawing, in which:

Fig. 1 is a diagrammatic view in perspective illustrating two terminals of a multi-channel communication and guiding system together with a chain of relay stations therebetween;

Fig. 16 is a block circuit diagram illustrating the modified transmitter equipment used to produce the beacon arrangement of Fig. 15; and

Fig. 17 is a block circuit diagram of a receiver arrangement for response to signals such as transmitted from the circuit of Fig. 16.

Referring to Fig. 1, there are provided two terminals 10 and 12 (west and east) interconnected by a chain of relay tower stations 13, 14 and 15. Of course, there may be many other repeater towers, only three being shown for purposes of simplifying illustration. Each of the towers is provided with a plurality of antennas 21, 22 and 21A, 22A, being directional, as indicated. Energy is transmitted from west to east with different characteristics between alternate towers, for example, at slightly different radio frequencies F1, F2, as shown in the drawing.

In the opposite direction, east to west, alternate frequencies, F3 and F4, are used. By the use of these different radio frequencies, interference of the signals by reason of overlapping of energy between the repeater towers is minimized. Antennas 21, 22 and 21A, 22A are preferably made sharply directional. At each of the towers are provided other antenna units 23 and 24 for transmitting and receiving communication signals to craft in the neighborhood of the various stations. The transmitting antennas 23 may transmit energy at the same frequencies F1 and F2, as used in the radio link system. However, the in-branching or incoming signals from the various craft are preferably at a different common frequency, herein shown as frequency F5.

Also mounted on each of the towers are a plurality of guiding beacon transmitting antennas 26 preferably provided with a directive reflector arrangement 26A. These beacons transmitters may operate at the alternate frequencies corresponding to the alternate frequencies F1 and F2, transmitted from the towers in the west-east direction. It should be clear that, if desired, the beacons may be arranged to cooperate with the east-west channels instead. At each of the intermediate towers in the zone of overlap of the directive radio beacon signals are provided separate marker beacon transmitting antennas 25 operating at a particular signal characteristic, for example, at the frequency corresponding to the next preceding radio beacon pattern. The arrangement of the guiding beacon and marker beacon system is provided for assuring that craft travelling along a line defined by the beacons will be enabled to switch from the reception of one of the frequencies to the next adjacent one in substantially the same area, regardless of the direction of travel of the craft. This function will be explained more fully in detail later.

A better understanding of the system shown in Fig. 1 may be had from the particular description of one embodiment of our invention as illustrated in Figs. 2, 3 and 4.

Referring to Fig. 2, the west terminal is shown to include a switchboard 50 containing jack connections for outgoing and incoming channels 1—N and 1a—Na, respectively. The switchboard is of known character provided for connecting telephone circuits or trunk lines to the proper channel jacks and also for connecting together incoming and outgoing channels under certain circumstances described hereinafter. Channel 1 includes a modulator 51 coupled to terminal 1. The modulator 51 and also all others from modulator 52 to the modulator for channel N may be of any desired type but are preferably of the character for producing "push-pull" time displacement modulation of pulses. In order to effect this time modulation, energy from a base wave source

60 is applied over individual phase shifters 62—67, etc., for channels 2 through N, respectively. Channel 1 need not have an individual phase shifter since the phase of the wave from source 5 60 may be applied directly without phase shift to the modulator 51. The phase shifters for the other channels are adjusted so that the individual trains of pulses for the separate channels will be displaced in time to provide a single resultant train in the common output 70.

Channel 1 has been chosen as the synchronizing and monitoring channel and, as such, is given a particular width W1 by shaper 58. The pulses of the other channels may be given a different width W2 in shaper 58a.

All the trains of pulses produced by the different channel modulators are combined, as indicated by the output connections at 70, and applied to an R.-F. translator 74 and radiated by 20 transmitting antenna 21. The R.-F. translator in this instance will provide a carrier wave of frequency F4, as indicated in Fig. 1. This train of multiplex channel pulses is east bound, channel 1 operating as a synchronizing and monitoring channel for controlling the separation of channel pulses at the receivers whether in a plane or at the east terminal 12.

In order that selected ones of the channels may be broadcast at terminal 10, another modulator 76 is provided. This modulator is coupled to the selected channels to be broadcast transmitted at a wider angle for communication with craft. Separate couplers 78 are provided to prevent the other channels coupled in parallel 35 to line 70 from also feeding to modulator 76. These branched signals are then transmitted from antenna 23 for a purpose of communication with craft as will be more readily understood when the particular description of Fig. 4 is given.

40 Before discussing the equipment and operation of the relay stations, let it be assumed insofar as the west base is now concerned that a west bound train of channel pulses 1a, 2a, 3a . . . Na is being received on antenna 21A, Fig. 2, and 45 that the pulses thereof are detected into video form at receiver 80. The video pulses of the incoming channels are applied to a pulse width selector 81. The video pulses passed by the selector 81 are applied to a demodulator 84, the 50 output of which is applied to the corresponding switchboard terminal.

Energy from the pulse width selector is also applied to the deblocking selectors of the other receiving channels, the energy being applied 55 through suitable delay devices for proper timing. Referring to channel 2a, for example, the deblocking pulse is applied to a delay device 90 and thence to deblocking selector 92 where it controls the selection of the pulses of channel 60 2a, as received over line 91, the selector excluding all other channel pulses. The channel pulses passed by the selector 92 are applied to demodulator 94 whereby the time displacement 65 of the video pulses is translated into an audio signal wave which, in turn, is applied over line 95 to the proper jack on the switchboard 50. This selector control is the same for the additional channels 3a to Na and therefore need not be illustrated or described in detail.

70 The return communication signals from the craft in the vicinity from the west base terminal are received on antenna 24 and detected to audio frequencies in a suitable detector arrangement 75. Detector 75 is provided with a channel selector system for separating the received sig-

nals in accordance with the selected channel and applying these signals to individual lines 71. A suitable selector for this purpose may be made in accordance with the teachings hereinafter more fully explained in connection with Fig. 3B. The separate output lines are connected over a cable 79 to the individual terminals 1a, 3a, 5a, 7a, etc., of switchboard 50.

In Fig. 3 is disclosed in more detail a typical block circuit diagram of the equipment provided with the repeater tower. Thus, as preferably shown, there are provided four directive antenna arrangements 21, 22, 21A, 22A, coupled to the receiver-transmitter units 32, 31 and 43, 47, respectively, of the repeater circuit. From the antenna 22 are applied pulses to the outbranching circuit 100 which serves to select the channels it is desired to transmit from antenna 23 for reception on the separate craft. These output signals are applied to antenna 23 over line 101. Carrier source 36 supplies energy at frequency F2 to energize beacon modulator 37 and the outbranching circuit 100. The energy received from the craft is applied from antenna 24 over line 103 to inbranching circuit 105 from whence it is supplied to antenna 22A together with signals from west bound transmitter 41. Energy from oscillator 48A is applied at frequency F3 to transmitter 47 and inbranching circuit 105. The inbranching circuit is timed by energy from receiver 43 as indicated by line 105a. The marker beacon antennas 25 are energized by transmitter 102 operating at the frequency F1, the same as that received on receiving antenna 22. For communication with aircraft antennas 23, 24 and 25 are preferably mounted above a shielding sheet 104 mounted on the associated tower. This sheet serves as an artificial ground for these antennas.

At the tower, the guiding beacon antennas 26 are provided within an angular reflector 26A which may be mounted on the tower in the manner illustrated in Fig. 1. The reflector arrangement is adjusted to cause the beacon antenna system to operate substantially unidirectionally. Furthermore, the horizontal portion of reflector 26A serves as an artificial ground to prevent much of the beacon energy from being radiated earthward to cause troublesome reflections and the consequent false course indications. It should be understood that, if the spacing above ground causes an unduly large number of lobes in the vertical plane, or too much trouble from ground reflection, the beacon antenna may be mounted directly adjacent the ground and the area therearound suitably cleared to prevent undesired reflecting action. The beacon antenna is illustrated only diagrammatically since the specific form of beacon used is not material to the principles of our invention. It is preferable to make this beacon as simple as possible and of such construction that little service is needed. Likewise, it is clear that the modulation may be produced either by keying the antennas alternately to shift the pattern or by modulating with different tone frequencies, such as 150 and 90 cycle tones commonly used in radio course beacons at the present. Moreover, each beacon may be caused to transmit identifying signals if desired as well as the directive indications.

Turning now to Fig. 3A, a more particular explanation of the out-branching circuit 100 will be given. The energy from the antenna 22 is applied to a detector 106 which detects the incoming waves to a video frequency. Since detection will

generally take place in receiver 31 if the pulses are to be transmitted at a different R. F. detector 106 may be omitted and the signal taken from the output of this receiver. The detected pulse envelope is applied to pulse width selector 108 which serves to select out the shaped pulses of channel 1. These pulses are then reshaped, if necessary, in shaper 110 after which they are applied over line 133 to modulator 134. The selected pulses from the output of 108 are also branched over delay circuits 113, 115, 117, 119 and 121 and shapers 114, 116, 118, 120 and 122, respectively, and applied to channel selectors 124, 126, 128, 130 and 132, respectively with the channel signals from detector 106 to select the pulses corresponding to channels 3, 5, 7, 9 and 11, for example. These selected channels properly timed with respect to channel 1 are then applied from the output of the respective selectors to line 133 from whence they are all applied to modulator 134. The output of modulator 134 is connected by means of line 101 to antenna 23, as shown in Fig. 3. Thus, the selected channels are broadcast for selection and reception by craft within the field of the communication system.

The operation of the in-branching circuit 105 may best be understood by reference to Fig. 3B. In this figure, the input line 103 is shown as connected to a detector 140 which serves to detect the received radio frequency to video frequency producing in the output a plurality of pulses corresponding to the channels received by antenna 24. In the form illustrated, each of these channels is represented by pulses of different widths. Accordingly, separate width selectors and demodulators are provided, as shown at 141, 143, 145, 147, 149 and 151. Just above selector 141 is provided a base wave generator 160 which is controlled by selector synchronizer 160a to produce a suitable base wave for timing these received channels for insertion into gaps in the east-west multiplexing channel of the system. Energy from this base wave generator is applied over separate phase shifters 161, 163, 165, 167, 169 and 171 to the separate pulse modulators 142, 144, 146, 148, 150, 152, respectively. In these separate modulators are produced time modulation pulse trains corresponding to channels 1a, 3a, 5a, 7a, 9a, and 11a, respectively. The output of all of these modulator circuits are combined and applied to modulator 172 which serves to modulate the carrier frequency F3. The resulting carrier frequency pulses are applied to the output of transmitter 47 for transmission together with the other multiplex channels. It should be understood, likewise, that in this particular case, instead of providing R.-F. modulator 172 in the in-branching circuit itself, these separate pulses could be applied to the input of the modulator in transmitter 47 used for the normal repeated channels.

In Fig. 4 is illustrated a typical receiver circuit for use on a craft, such as an aircraft, for receiving the communication and guiding signals from the tower of the system in accordance with our invention. In this circuit, there is provided aircraft receiving antenna 180 which receives the beacon signals and the communication signals transmitted from the tower by means of antennas 23 and 26. Antenna 180 is preferably coupled to a broad band receiver 181 tuned sufficiently broadly to receive both carrier frequencies F1 and F2. In the output of receiver 181 are provided amplifying filter arrangements 182, 184 tuned to pass frequencies F1 and F2, respectively. When the craft is in such a position that

energy at F2 predominates, the output from 184 may be applied to an automatic volume control circuit 186 which serves to bias 182 so that substantially no energy at F1 passes. Similarly, when the craft passes to a region where F1 predominates A. V. C. circuit 188 in the output of 182 biases circuit 184 so that substantially no energy at frequency F2 is passed. Thus, as the craft travels along a course defined by the radio beacons of different frequencies, the receiver on the craft is made to respond to one of these signals to the exclusion of the other. It should be understood that other signal characteristics different from frequency discriminations may be used to operate the receiver switching if desired. The receiver energy is then detected in detector 187 to provide an envelope of the form shown in Fig. 4A. This envelope has a low frequency wave component 215 corresponding to the beacon signals and a pulse component 216 corresponding to the pulse communication signals. This composite wave from the output of detector 187 is applied to a limiter 190 which serves to clip or limit the envelope at a level 217 preferably substantially at twice the average incoming carrier frequency so that the low frequency envelope 215 will be passed but the high energy pulses will be limited in amplitude. The output of limiter 190 is then applied to a selective filter 191 which serves to remove the higher frequency pulse components still remaining and this output signal is then applied to a guide indicator 192 or to other visual or audible indicators, if desired.

The envelope wave is also passed to a clipper 193 which serves to remove the portion of the envelope below clipper level 217 to separate the incoming pulses from the lower frequency envelope and apply them to the selective circuit. These pulses are applied to a pulse width selector 194 which serves to select the pulses of channel 1 and apply them to a demodulator circuit 195 from which they are applied to headphones or other audible signal source 196. These pulses of channel 1 are preferably order channel impulses used for communicating to all of the planes or other craft in the region and also may serve for selecting another channel. Accordingly, the pulses from the output of pulse width selector 194 are applied to an adjustable delay circuit 197 which serves to adjust the delay of the pulses in the output of this selector to a proper position for selection of other communication channels from among those received at 181. These output pulses are applied to a de-blocking selector 198 together with the clipped pulses from the output of clipper 193. In selector 198 the desired channel is selected by adjustment of delay circuit 197 and these selected pulses are applied to demodulator circuit 199 and from there to headphones 200.

For the return communication a microphone 201 is associated with the other channel receiver 196 and applies pulses to a pulse modulator 202. A control wave source 203 is provided for properly timing modulator 202. If desired, the control wave source may be synchronized with the output pulses from adjustable delay network 197 or directly from the output of selector 194. This control wave, together with the audio signals from 201, produce in the output of modulator 202 pulses time displaced in accordance with the signalling energy applied. These output pulses are then shaped to a desired width in pulse shaper circuit 204 and applied to radio fre-

quency modulator 211. A wave of carrier frequency F5 is also applied to modulator 211 from a source 210 so that the combined signals may be radiated from antenna 212 for reception on antennas 24 of the link channel. In addition to the control channel transmitter, is provided a communication channel transmitter including a microphone 206 and a pulse generator and modulator 207. Output energy from control wave generator 203 is applied over a phase shifter 205 to pulse generator 207 for the purpose of properly timing these pulses to prevent overlapping of the pulses from modulator 202. The output pulses from modulator 207 are applied to a pulse shaper 208 which serves to adjust the pulses in width to correspond with any one of the channels 1a, 3a, 5a, 7a, 9a and 11a, which are used for communication between the plane or other craft and base station. These pulses are then also applied to modulator 211 for transmission over antenna 212.

It is clear that the signals transmitted from the craft equipment will be received in the tower equipment, such as shown in Fig. 3, and demodulated and properly timed for application to the multiplex channel in proper timed relationship.

A better understanding of the beacon operation may be had from the following description made with reference to Figs. 5 and 6 of the drawing. As shown, each of the communication mediums for the two directions comprises a series of repeaters having field patterns shown diagrammatically in Fig. 5 at 220, 221, 222, 223 and 224 for the eastbound traffic and 240, 241, 242, 243 and 244 for the westbound traffic. In addition, the beacon signals transmitted from the succession towers are shown at 225, 226, 227 and 228 of Fig. 5. This unidirectional pattern is preferably made to have considerable energy component in the vertical plane so that aircraft may follow the course at many different altitude levels. Preferably, each of these guiding beacon patterns is produced by two relatively narrow overlapping patterns 225, 225a, 226, 226a, 227, 227a, 228 and 228a, as can be more clearly seen in Fig. 6.

It should also be realized that there may be a number of vertical maxima and minima points in the radiation lobes of the beacon patterns when the antennas are mounted high above the earth. For this reason, it is desirable that the receiving switching system be not made too sensitive since, at the fringes where the succeeding patterns tend to overlap one another, there might be caused a number of reversals and switches from one pattern to the other before sufficient domination of one of the radiation patterns was achieved. Because of the difficulty in maintaining perfect alignment of the beacon stations, this switching action would be very confusing on the pilot, as it would tend to show him suddenly bearing a considerable distance from the course. By making the receiver switching less sensitive so that considerable amplitude difference is required for the switching action, this oscillation of the receiver circuit between the two conditions at the points of overlap of the patterns may be avoided.

Because of the safety margin provided in sensitivity, an aircraft such as shown at 222A proceeding from the west to east would have to cross the boundary of the overlapping zone of radiation patterns 226 and 227 to some point such as indicated by the dot 225A before the automatic switching could take control. On the other hand, an aircraft such as 222B travelling in the op-

posite direction, would have to pass out of the influence of radiation pattern 227, for example, and considerably into the field of the next succeeding radiation pattern 226 to some point, such as shown at 225B before the switching over of the receiver would be effective. This would result in aircraft travelling in opposite directions switching over their control at different points along the path. Such variation in switching points is generally not desirable particularly in view of the communication with the base station mounted on similar type receivers. In order to assure that aircraft travelling in opposite directions will be switched over for reception of the next succeeding pattern in substantially the same zone or area, regardless of the direction of travel the additional marker beacons 230, 231, 232 and 233 may be provided. These beacons, as shown, are made to have patterns slanting forward in the direction of the repeater stations because of the particular characteristic shape of the guiding beacon radiation patterns. Thus, craft 222A travelling west to east from one beacon to another will still be switched at substantially the same point 225A. However, craft 222B travelling in the opposite direction will have its receiver switched by means of the energy in the marker beams 230 to 233, respectively, so that the switching over will take place in substantially the same area as that of planes travelling west to east. In the case of plane 222B, for example, it will be switched over at about point 225C. These marker beams are preferably made relatively narrow in the line of travel of the craft and relatively wide transversely thereto as shown in Figs. 5 and 6.

Fig. 6 may be considered as a plan view in cross section along lines 6—6 of Fig. 5. This type of illustration is preferable since the marker beams 230—233 are arranged at an angle and an accurate plan view would therefore be less clear.

While we have shown preferably the use of uni-directional radio beacons, it is clear that bi-directional beacons may be used, if desired. Likewise, it is clear that the beacons need not be provided at each repeater station but may be provided at discretely placed intervals so that adequate overlapping patterns are produced.

In order more clearly to understand the operation of the multiplexing system, as shown in the preceding figures, reference is made to Fig. 7. In this figure, curve *a* represents several trains of pulses corresponding to the respective channels. It will be seen that the succeeding channels 1 to 12 for example, are spaced in time so that they do not overlap. Likewise, channel 1 is shown to be composed of pulses of a different width from the other channels for the purpose of selectively timing the remote receiving equipment. The timing of the channels at the transmitting end, for example, at the west base, may be accomplished by means of apparatus described more fully in connection with Fig. 8. A rectified wave 250 may be provided to produce channel 1 and by phase shift a different rectified wave 251 used for production of the next succeeding channel. The progressive phase shift of the control wave may be used successively to time the other channels of the system in a similar manner.

In curve *c* the selected channels 1, 3, 5, 7, 9 and 11 are illustrated in extended form with respect to the showing of curve *a*. These pulses may, for example, represent the substantially evenly spaced pulses branched out at the control towers for communication with the craft. Separation or selection of the channels may be obtained by

delaying pulses 1 different amounts so that they coincide in position with the pulses of successive channels, 3, 5, 7, 9 and 11, as shown in curve *d*. If these pulses are then combined and clipped at level 252, the channels may be separated out from the entire group of channels. For example, if a single channel is to be selected as shown in curve *e* pulse 1 will be delayed to position it in time to coincide with channel 5 for the selection of this particular channel.

In curve *f* are shown pulses of different width which may be used on the craft to indicate separate reply channels 1b, 3b, 5b, 7b, 9b and 11b which may correspond to the channels 1, 3, 5, 7, 9 and 11 transmitted to the craft. These separate channels are selected at the tower in accordance with pulse width, as was explained more particularly in connection with Fig. 3B. A more complete description of the pulse width selector apparatus is made hereinafter in connection with Figs. 10 and 11.

In order more clearly to disclose the structural examples of a pulse generator and modulator suitable for use in the transmitter circuits of Figs. 2, 3 and 4, reference may be had to the circuit diagram of Fig. 8. Signal energy for channel 1, Fig. 2, for example, is applied to modulating circuit 51, the output of which is coupled to the outgoing line 70. The input signals are applied to the grid circuit of coupling tube 300. The wave from tube 300 is applied over separate transformer windings 304 and 305 to a mixing transformer arrangement 303. Simultaneously, energy from base wave generator 60 is applied to mixing transformer 303 by means of coil 306. Secondary coils 307 and 308 are also coupled to transformer 303 to extract from there the mixed signals. Coils 307 and 308 are coupled to a pair of triode amplifiers 309 and 310 asymmetrically biased by batteries 311, 312 for operation in the manner of an offset full-wave rectifier. The base wave of generator 60 preferably has a frequency corresponding to the desired cadence frequency *T* of the pulses to be produced.

Since tubes 309 and 310 operate in effect as an offset full-wave rectifier, an output wave of the form shown at 314a will be produced in the absence of any input signals. This wave is applied to a pulse shaper 314 which clips and shapes the cusps of wave 314 to produce a plurality of unevenly spaced pulses (see dotted line pulses of pulse train 315) having cadence frequency *T*. Upon application of energy over channel connection 317, the effective bias of the push-pull circuit of tubes 309, 310 is changed producing pulses having different displacement in push-pull as indicated by curve 313 and the solid line pulses of pulse train 315. This displacement represents applied energy of one sign, for example, positive. The displacement will also take place in the other direction for applied energy of different sign so that the pulses will be displaced further from symmetry. Thus, as the signals are applied to modulate the base wave, a time displacement of the pulses in the output of pulse shaper 314 is provided. While Fig. 8 discloses a modulator circuit for block 51 of Fig. 2, it is clear that the same type of modulator may be used in all of the different pulse generator and modulator circuits of the system. For a further description of this type of modulator, reference may be made to the copending application of E. Labin and D. D. Grieg, Serial No. 455,897, filed August 24, 1942.

A typical demodulator circuit for time modu-

lated pulses is shown in Fig. 9. This circuit corresponds to the combination of deblocking selector 81 and demodulator arrangement 84 hereinbefore referred to in Fig. 2. It should be distinctly understood, however, that the demodulator 84 of this circuit may be used for demodulation in the other parts of the system.

According to the arrangement of Fig. 9, the train of pulses 321 is fed over line 33a to mixer tube 320 of the deblocking selector 92. At the same time, deblocking pulses 323 from delay circuit 90 (Fig. 2) are fed to another separate grid of tube 320 over line 322. These deblocking pulses serve to produce, in conjunction with the selected incoming pulses timed to add hereto, an output series of pulses from tube 320. Assume, for example, that channel pulses of 321 are applied to the selector 91, the delay line will operate to provide a series of rectangular pulses, 323 timed in spaced relation according to the pulses of channel 3. These combined pulses may have the form shown in curve e, Fig. 7. Tube 320 is also biased to serve as a clipper so that only the boosted pulses of the selected channel appear in the output thereof. A D. C. restorer rectifier tube 330 may be provided across the input of the deblocking pulses 323 to assure that the incoming deblocking pulses are of a proper level to work with the clipper circuit of tube 320 to leave only the desired output pulses above clipping level.

The output pulses from tube 320 have the same cadence frequency T as the original modulated pulses 315 from modulator 303, Fig. 8. The pulses are applied to the control grid of a demodulator tube 340 and cause tuned circuit 341 connected to another grid of this tube to oscillate at the tuned frequency producing in the tube 340 a combined grid potential in the form of a combination of the wave generated in 341 and the incoming pulses. Circuit 341 is preferably tuned to some harmonic of the cadence frequency of the input pulses so that as the repetition rate is varied, due to the modulation signals, the output pulses will be raised to different levels depending upon their time displacement. Accordingly, in the output of tube 340 will appear a modulation envelope of pulses carrying signal modulations thereon. For a further understanding of the principles of this type of demodulator, reference may be had to the copending application of D. D. Grieg, S. N. 459,959, filed September 28, 1942.

A low-pass filter 345 is provided to remove from this demodulated signal envelope the pulses of higher frequencies that define the signal envelope.

While the pulse width selectors of Figs. 2 and 3 may comprise any circuit arrangement capable of segregating a pulse of a given width from pulses of greater and/or lesser widths, we have shown in Fig. 10, for purposes of illustration, a suitable circuit which, depending upon selection of circuit constants, is capable of distinguishing between two pulse widths differing by as little as one hundredth of a microsecond. Such fine distinction, however, is not necessary except where selection among a very large number of different pulse widths are required between close limits.

The circuit of Fig. 10 preferably includes a limit clipping stage 350 as an input coupler which limits all input pulses to substantially the same amplitude. Should the input pulses be of a positive polarity as indicated by the pulses of curve 11a in Fig. 11, the coupled stage 350 also serves

to reverse the polarity as indicated by the pulses of curve 11b. This output pulse energy from stage 350 is applied through a resistor R to a shock excitable L-C circuit 355. Connected across the tunable circuit 355 is a vacuum tube 360, the cathode 361 of which is connected to the input side of the circuit 355, while the anode 362 is connected to the opposite side 363 of the tunable circuit. The side 363 is also connected to a source of anode potential 364. The pulse energy, curve 11b, from the anode connection 354 is applied to the grid 365 of the tube 360 so as to block the conduction between the cathode 361 and the anode 362 while pulse energy is applied to the circuit 355. The undulations produced in the circuit 355 in response to pulse energy over anode connection 354 are taken off through a connection 370 for application to a threshold clipping amplifier stage 375. The bias on the grid 376 is controlled by adjustment of resistor 377. In the output 378 of stage 275 is a pulse width shaper 380, the operation of which is herein-after described.

Assume, for purposes of illustration, that the widths of the pulses of curves 11a and 11b correspond, respectively, to channels 1, 3, 5, 7 and 9, as indicated by the width reference characters W1, W3, W5, W7, and W9. Assume also that the circuit 355 is tuned for selection of pulse width W5. Curve 11c represents the output of the circuit 355 when the circuit 355 is tuned for selection of pulse width W5, illustrating the different output undulations for the different pulse widths of curve 11a. When the leading edge 381 of the pulse W5 is applied at negative polarity, as indicated by curve 11b, to the circuit 355, an initial undulation 382 is produced which is normally followed by undulations 383, and so on in the form of a damped wave. When the circuit 355 is tuned to a frequency, the period of which is exactly twice the width W5, the trailing edge 386 occurs where the initiated oscillatory energy crosses the zero axis from undulation 382 to undulation 383. Since the trailing edge 386 shock excites the circuit in the same direction at this point, an undulation 387 coinciding substantially with 383 produced thereby in the circuit 355 adds algebraically to the undulation 383 to produce undulation 390. The next 50 succeeding pairs of undulations produced by the leading and trailing edges of pulse width W5 would normally tend to produce a negative undulation which would continue as a damped wave. The damping tube 360, however, eliminates the 55 trailing oscillations so that they do not interfere with the undulations produced by subsequent pulses applied to the circuit 355.

A pulse width less than pulse width W5, such, for example, as pulse widths W1 and W3, will 60 not produce maximum undulations as great as the undulation 390 for the tuning adjustment corresponding to pulse width W5. This is illustrated by the undulations 393 and 394 produced in response to the pulse widths W1 and W3, 65 respectively. The reason for this is readily apparent because the shock excitations produced by the leading and trailing edges of the pulses of lesser width than W5 are, in part, opposed to each other, as indicated by the broken lines 70 associated with the undulations 393 and 394. The undulations 395 and 396 produced in response to the greater pulse widths W7 and W9 are likewise smaller than the undulation 390 since here again the oscillations produced in response 75 to the leading and trailing edges of the greater

pulse widths are in part opposed to each other so that the algebraic summation thereof is less than in the case of the undulations produced in response to pulse width W5.

The threshold clipping stage 375 is adjusted to clip at a level 397 thereby obtaining and amplifying the crest portion 390a of the undulation 390, as indicated by curve 11d. The pulse shaper 380 is preferably of the character adapted to differentiate the pulse producing the pulse shape of curve 11e. The shaper also includes a clipper stage for clipping the positive pulse portion of pulse shape 390b at level 398 thereby producing a narrow width pulse 390 curve 11f synchronized in time to the pulse of width W5. Thus, any time modulation applied to the pulses of width W5 will carry through to the output pulse 390c which may be demodulated to an audio wave by the demodulator. It will also be readily apparent that, by adjusting the tuning of circuit 355 to another frequency, the period of which is twice the duration of any one of the other pulse widths of curve 11a, that a corresponding output pulse will be produced representing the pulses of the pulse width selected.

In Fig. 12 is shown a modified form of terminal equipment which may be used to replace the terminal equipment of Fig. 2. The receiving part of the terminal has not been illustrated since it is not necessary to an understanding of the invention and its general operation will be clear from the receiver equipment illustrated in Fig. 13. In accordance with Fig. 12, a plurality of channels 1 to N are shown connected to a switchboard 400. Energy from channel 1 is applied over a filter 401 to channel modulator 402. At the same time, a synchronizing frequency f , preferably a given sub-harmonic frequency of the pulse cadence frequency, is applied from synchronizing signal generator 403 to modulator 402. Energy from control wave source 404 is also applied to modulator 402 to provide the pulses which may be time modulated in a manner as described above. Filter 401 is tuned to remove from channel 1 all the components of frequency f so that they will not cause accidental operation of the selector circuit described in more detail herein-after in connection with the tower receiver circuit.

In addition to the regular channels 2, 3, 4, 5, 6, 50 etc., we provide a further channel for switching on the beacon transmitters and the aircraft out-branching transmitters at the towers (Fig. 13) from the control station, Fig. 12. For this purpose energy from base wave source 404 may be applied over phase shifter 405 and switch 407 to the tower control channel modulator 406. This modulator produces a pulse channel properly spaced from the other communication channels in time. The series of pulses defining this control channel are shaped in a shaper 408 all to have a particular width. It is clear that instead of a particular with other characteristic designations could be applied to the pulses so that they may be segregated at a receiving station. Other channels are all applied with proper phase shift by means of phase shifters, such as 415 and channel modulator 416 to the common line 410. These pulses are then used to modulate radio frequency energy from oscillator 417 in modulator 418 to transmit a pulse modulated high frequency wave.

In Fig. 13 is illustrated a typical tower installation designed to cooperate with the transmitter terminal shown in Fig. 12. The repeater portion 75

of this tower equipment comprising antennas 21, 22, 21A, 22A, detectors 31, 43, modulators 32, 47 and radio frequency sources 36, 48 may be identical with similar illustrations shown in the preceding figures. From the output of detector 31 are branched over line 450 the video frequency pulses representing the channels. These pulses may be applied to a deblocking selector 452. The output from deblocking selector 452 is applied to demodulator 453 which serves to demodulate the pulses to produce audio frequency. A deblocking oscillator 455 operating at a frequency slightly lower than the normal pulse cadence frequency of the incoming channels is provided to deblock selector 452. Thus, different channels are progressively selected until channel 1, the synchronizing channel, is received. Deblocking oscillator 455, is tunable in response to a harmonic of synchronizing frequency f , which was preferably modulated on channel 1. This harmonic frequency of f is the same as the pulse cadence frequency of the channel. This synchronizing frequency is separated by filter 454 from the output of demodulator 453 and applied to tune deblocking oscillator 455 as soon as pulses of channel 1 are reached in the channel traverse of the deblocking oscillator 455. Thus, when channel 1 is demodulated, the deblocking oscillator 455 is pulled into step with the cadence frequency of the incoming pulses. This channel may now be used to provide a control wave for selecting the other channels.

The deblocking signals from oscillator 455, as it is synchronized, are applied over phase shifter 35 458 to deblocking oscillator 459 for selection of another channel. The other channels which are to be branched off at this station may be selected in a similar manner. These selected channels including the output of deblocker selector 452 40 may then be applied over line 456 to a modulator 457 for transmission from antenna 23 to the craft. A more particular description of the deblocking oscillator selector may be had by reference to a copending application of D. D. Grieg, Ser. No. 514,998, filed December 20, 1943.

In accordance with the arrangement shown in Fig. 13, however, modulator 457 and the aircraft beacon signalling equipment 31, 38, as well as the beacon oscillator 475 and the marker beacon oscillator 476 are normally deenergized. By means of a suitable trigger circuit, these various transmitters may be energized by the special control pulses transmitted from station 12. These control pulses are of a given width and consequently may be selected by pulse width selector 460 and detected in detector 461. This detected energy is applied over transmission line 462 and coupling circuit 463 to a control grid of a gas trigger tube 464. Upon application of these signals, tube 464 is triggered into operation energizing relay magnet 470 causing the closure of relay switch 471. Switch 471 couples power supply source 472 to beacon signal modulator 37, beacon signal generator 38, channel modulator 457 and oscillators 475 and 476, causing these circuits to go into operation and thus transmitting energy out-branched for communication with the craft as well as the beacon signals for guiding the craft and the marker beacon for effecting the desired switching. It should be understood that all of the towers along the chain may be turned on from the base station for guiding of craft when desired.

Most of the craft are preferably provided with transmitter equipment which may be used selec-

tively to turn on the beacon and the communication equipment by energy transmitted from the craft itself. This operation may be more clearly understood from a description of the in-branching features of tower equipment shown in Fig. 13. The incoming signals from the craft are received on antenna 24 and applied to a detector circuit 480 which serves to detect these signals to envelope frequencies. Associated with the detector equipment is the carrier rectifier unit 481 which may be similar to units commonly used for automatic volume control and responsive to the energy level of the incoming carrier frequency. This rectified carrier is applied over coupler unit 463 to the grid of trigger tube 464. Operation of tube 464 serves to furnish power supply to the modulators and oscillators in the same manner as when the tube is triggered from the control terminal station. It should be understood that generally craft traversing the course will keep their transmitters turned on even when they are not using them for actual communication. The carrier energy thus received in the successive antennas will serve to turn on the beacons for guiding craft along the course. Only those beacons within the field of radiation of the aircraft transmitter will be turned on at one time. Preferably, this field is sufficiently great to include two or more beacon transmitter units so that a continuous path of guiding signals may be furnished.

In addition to the provision of the triggering circuit for energizing the radio beacons, the energy detected at 480 contains communication channels. In the system, as illustrated, it is contemplated that the communication channels be each applied to sub-carrier frequencies which differ from one another so that they may be readily separated by selective filters. Thus, the separate channels received at 480 may be separated in selective filters 482, 483, 484, etc., and demodulated to reproduce the audio signals. These detected audio signals are applied to separate channels modulators 485, 486, 487 for transmission over line 495 to carrier frequency modulator 47 for the purpose of carrying on the desired communications. Modulators 485, 486, 487 are controlled in time position to fit properly into channels transmitted from modulator 47. A base wave generator 465, for example, may be synchronized with energy from deblocking oscillator 455 to produce a control wave of the desired frequency. This control wave may be applied over separate phase shifting units 491, 492 and 493 to the respective modulators 485, 486 and 487 to assure proper time spacing of the channels with respect to the other multiplex channels being transmitted.

It should be distinctly understood that the triggering circuit shown in Fig. 13 is not dependent on the particular type of separation used for the multiplex channel nor, indeed, on the transmission of multiplex channels at all. It should be understood that the various portions shown in Figs. 12 and 13 may be substituted in Figs. 2 to 3, inclusive, and vice versa, if desired, or that other types of signal equipment may be used.

For particular cooperation with the tower equipment shown in Fig. 13, we provide aircraft communication equipment shown in Fig. 14.

Referring now to Fig. 14, the aircraft communicating equipment is shown to comprise a broad band amplifier 520 whereby the out-branching channel pulses transmitted by the tower antenna 23, Fig. 12, are received. The received out-branching channels in broad band amplifier 520

may be applied to selective filter amplifiers 500, 501 which serve over automatic volume control circuits 502, 503 to render one or the other of the filter amplifiers effective in the same manner as explained more fully in connection with Fig. 3. The selected frequency is thereafter applied over branched circuits to clipper 521 and limiter 523. The energy in the output of limiter 523 is applied over a filter 524 to an indicating instrument 525 to show the course beacon indications. The output of clipper 521 is applied to a detector 530 which serves to detect the carrier envelope of the pulses to the video frequency. The video pulses are applied to a synchronizing unit similar to that described in connection with Fig. 13 whereby the synchronizing signal of channel 1 synchronizes the receiver equipment to the timing relationship of the out-branching channel pulses. The deblocking oscillator 567 produces a deblocking pulse timed to each pulse of channel 1 so that the selector 561 will pass the pulses of channel 1 which are demodulated at 564 and the audio signals thereof passed by filter 565 to earphones 551. The deblocking pulses produced by the oscillator 567 are applied to an adjustable delay device 552 over connection 553 where the deblocking pulses are delayed a selective amount depending on the adjustment for deblocking a selected one of the out-branching channels 3, 5, 7, 9 and 11. As shown, the device 522 is adjusted to provide a delay sufficient to time the deblocking pulses for the pulses of channel 3 so that by application of the delayed deblocking pulses to selector 555, the selector will pass only pulses of channel 3. The channel 3 pulses are then demodulated by demodulator 556 and the output thereof applied to earphones 557.

It will be readily apparent from the foregoing description that by changing the adjustment of the delay device reception may be had over any one of the channels 3, 5, 7, 9 or 11. In normal operation, the operator at the base terminal will designate over an order channel, in this case channel 1, which channel the operator at the plane is to use in receiving a message and also which channel he may use in replying to same. Should the out-branching channel designated be channel 5, the delay device would be changed to the adjustment No. 5 and the phone 327 would then receive messages coming over channel 5. This adjustment of the device 522 would preferably be by some simple step by step system.

The transmitting equipment 530 for the aircraft is shown in this embodiment to comprise A. F. modulation of sub-carrier waves, a different sub-carrier wave being selected for each channel. In-branching channel 1, or in other words, the order channel from aircraft to terminal, is transmitted by an R. F. translator 532 coupled to an antenna 533 to which voice or other intelligence signal is applied over microphone 534 and audio amplifier 535. The sub-carrier wave is supplied by any known form of suitable oscillator banks 540, having separate output terminals 541, 542 each providing a different frequency. Output connection 541 provides a sub-carrier frequency f_a for inbranching channel 1. This frequency is applied to the translator and thus serves as the sub-carrier for the intelligence received at microphone 534. The output connections 542 through connection 546 provide carrier frequencies f_b , f_c , f_d , f_e and f_f , respectively, to frequency selector 550 where, by a movable contact 351 or other selective arrangement, selective connection with one or the other of the output connections 542

to 546 may be made for application of the sub-carrier energy thereof to R. F. translator 549. It will thus be clear that by proper selection of the sub-carrier, a reply to conversation received over any one of the out-branching channels may be made over any designated in-branching channel frequency.

In the previously described embodiments of our invention we have shown a system in which the receiver is switched from one frequency to the other in response to a comparison of the amplitude of the received carrier frequencies. It is clear that this switching function may be performed by other types of switching signals. Using such switching signals, it is not necessary to provide at the repeater stations additional transmitters of different carrier frequencies with the consequent necessity of providing extra oscillators. One such modified system is illustrated in Figs. 15 to 17 inclusive.

Turning first to Fig. 15, there are shown three beacon radiation patterns 225, 226 and 227 operating at frequencies F1, F2 and F1, respectively. In the area of overlap of each of the beacon patterns is provided a pair of marker beacon radiations, as shown at 600, 602, 600a and 602a. Assuming a craft is travelling from west to east from pattern 226 to pattern 227; the receiver on the craft is provided with specially responsive circuits responsive to particular audio frequency tones or other signalling. As the plane progresses, it first passes into the field of beacon 602. Beacon 602 has a carrier frequency of F1, together with a particular tone modulation of 900 cycles, for example. In the receiver is provided equipment responsive to the 900 cycle note which tends to switch the tuning of the receiver-detector unit to carrier frequency F2. However, since the receiver is already operating at that frequency, nothing occurs. As the craft progresses it comes within the field of beacon 600 which carries a tone modulation of 500 cycles on the carrier frequency F1. In the receiver a special response circuit responds to tune receiver to frequency F1.

A craft travelling from east to west from pattern 227 to 226 will first encounter beam 600 which has no effect on the receiving equipment and then will receive beam 602 which serves to switch the receiver from response to F1 to F2. Similar switching effects are produced at the intersection of the other beacons by marker beams, such as 600a, 602a. It is clear, however, that in going from F2 to F1 in the east-west direction the tone frequencies must be reversed in order that the switching be accomplished in the desired direction. Instead of the particular tone frequencies it is clear that other distinctive signals may be used if desired.

In Fig. 16 is shown a portion of a tower or beacon transmitting equipment similar to that shown in Figs. 3 and 13. However, the circuit has been modified in this arrangement to provide for the two separate marker beacon signals. A common carrier frequency source 620 is provided to supply carrier energy to the normal out-branching circuit 100 from whence it is transmitted over antenna 23 and to the outgoing transmitter and to the course beacon modulator, not shown. This carrier frequency is also applied to individual modulators 621 and 622 which are coupled to antennas 625 and 626, respectively. A source of signal frequency 623 furnishing the 500 cycle modulation energy is coupled to modulator 621 and a separate source 624 to 900 cycle energy is

coupled to modulator 622. Thus, the separate marker beams are produced in the proper position in the area of overlap of the incoming beacon signals. It should be distinctly understood that this type of system may be applied equally well to the circuits of Figs. 3 or 13, as desired, in place of those shown or to other forms of beacon arrangements within the scope of our invention.

In Fig. 17 is shown an aircraft receiver suitable for use with the beacon system of Figs. 15 and 16. In accordance with this arrangement, energy is received on antenna 180 and applied to a broad band amplifier and detector 610. The output of this broad band receiver is applied to a sharply tuned detector stage 611 and to a broadly tuned detector stage 612. In the output of 612 are provided two filters 655 and 658 which serve to pass the 900 and 500 cycle tone frequencies, respectively. The 900 cycle tone energy from the output of filter 655 is applied to a relay magnet 656 which, upon energization, serves to operate a plunger control 657 which tunes the detector 611 to frequency F2. Detector 611 is provided with any known form of tuning system such as is common in push-button controlled receivers and remains tuned to this frequency. The output signals from detector 611 are passed to limiter 190, filter 191 and indicator 192 and to closure 193 and the voice channel selector and demodulator 650 in the same manner as in the other receivers described. When the receiver passes into a beam modulated with the 500 cycle note, this 500 cycle note is selected as filter 658 and applied to relay magnet 659 which serves to operate plunger 660 to tune detector 611 to the new frequency F1. The receiver is thus made selectively responsive to F1 or F2 dependent upon the relay last operated. If more than two frequencies are provided a corresponding change may be made in the control transmitters and the receivers to accommodate these additional frequency changes.

It can be seen that with this particular switching arrangement aircraft may travel in either direction west to east or east to west, along the course defined by beacons of Fig. 15. Likewise, the switching will take place at different predetermined points which are substantially in the same area, regardless of the direction of travel of the craft.

While we have given, by way of example, some specific preferred embodiments of systems operating in accordance with our invention, it is to be understood that these illustrations are not to be construed as limitations on our invention. Many modifications of our invention will occur to those skilled in the art. Accordingly, the scope of our invention is to be determined by the objects set forth herein and in the accompanying claims.

What is claimed is:

1. A radio beacon system for guiding craft provided with switching apparatus along a predetermined course, comprising guiding radio beacon means arranged at spaced points along said course and aligned to provide radiation patterns overlapping along said course, successive ones of said beacons having different signal characteristics, marker beacon means arranged in the area of overlap of said guiding beacon radiation patterns adjacent each of said points, and means for applying signal energy of predetermined signal characteristics to said marker beacon means for operating switching apparatus on said craft.
2. A radio beacon system for guiding craft

along a predetermined course, comprising guiding radio beacon means arranged at spaced points along said course and aligned to provide radiation patterns overlapping along said course, successive ones of said beacons having different signal characteristics, marker beacon means arranged in the area of the overlap of said guiding beacon radiation patterns adjacent each of said points, and means for applying signal energy of the characteristics of one of said guiding beacons to said marker beacon means.

3. In a radio guiding system for guiding craft along a predetermined course wherein a plurality of unidirectional guiding beacons are aligned so that their radiation patterns overlap along said course in the vicinity of the succeeding beacon, the successive ones of said beacons operating at different carrier frequencies, marker beacon means for producing a radiation pattern transverse of said course in the area of overlap of said beacons, and means for energizing said marker beacons at a frequency corresponding to that of the frequency of one of the overlapping beacon fields.

4. A radio beacon system for guiding craft along a predetermined course, comprising guiding radio beacon means arranged at spaced points along said course and aligned to provide radiation patterns successively overlapping along said course, successive ones of said beacons having different signal characteristics, mobile receiver means for movement along a course in the radiation fields of said beacons, control means for rendering said mobile receiver responsive to successively receive energy characteristics of the successive beacons in the line of travel of said craft, radiating means for providing radiated control signals in the area of overlap of said guiding beacon radiation patterns and means in said mobile receiver means responsive to said radiated control signals for operating said control means.

5. A system according to claim 4, wherein said last named means comprises circuit means responsive to different frequencies for operating said control circuit.

6. A system according to claim 4 wherein said radiating means comprises marker beacon means, and means for giving to said marker beacon means the characteristics of said control signals.

7. A system according to claim 4, wherein said radiating means comprises two marker beacons arranged in said area of overlap and spaced apart a short distance along said course line, separate control signal sources of different signal characteristics, and means for applying signals from said control signal sources to separate ones of said marker beacons, and wherein said last named means comprises means for operating said control means to tune said receiver to the energy from the guiding radio beacon next adjacent the marker beacon.

8. A radio beacon system for guiding craft along a predetermined course, comprising guiding radio beacon means arranged at spaced points along said course and aligned to provide radiation patterns successively overlapping along said course so that in at least one direction along said course one of said overlapping fields is relatively weak with respect to the other field, successive ones of said beacons having different signal characteristics, mobile receiver means for movement along a course in the radiation fields of said beacons, control means in said mobile receiver responsive to said different signal characteristics for rendering said receiver means responsive to

the next successive beacon in the line of travel of said craft, marker beacon means arranged in the area of overlap of said guiding beacon radiation patterns and means for applying signal energy of said signal characteristics to said marker beacon for causing said receiver to become responsive to the next successive guiding beacon signals in substantially the same area, regardless of direction of movement along said course.

10. A radio beacon system for guiding craft along a predetermined course, comprising guiding radio beacon means arranged at spaced points along said course and aligned to provide radiation patterns successively overlapping along said

15 course, so that in at least one direction along said course one of said overlapping fields is relatively weak with respect to the other field, successive ones of said beacons having different signal characteristics, mobile receiver means for movement along a course in the radiation fields of said beacons, control means in said mobile receiver responsive to said different signal characteristics for rendering said receiver means responsive to the beacon of predominant signal strength,

20 marker beacon means arranged in the area of overlap of said guiding beacon radiation patterns, and means for applying the signal energy of the characteristics of the guiding beacon having the relatively weak field in the area to said marker

25 beacon to provide a sharp change in field strength in the area of overlap to assure operation of said receiver to change its condition of reception at substantially the same point, regardless of direction of movement along said course.

30 10. A radio beacon system for guiding craft along a predetermined course, comprising guiding radio beacon means arranged at spaced points along said course and aligned to provide radiation patterns overlapping along said course, successive

35 ones of said beacons operating at different radio frequencies, mobile receiver means for movement along a course in the radiation fields of said beacons, control means in said mobile receiver responsive to said receiver triggering signal for ren-

40 dering said receiver means responsive to the beacon of predominant signal strength, and means effective in the area of overlap of said guiding beacons for producing a receiver triggering signal to assure operation of said receiver to 45 change its condition of reception at substantially the same point, regardless of direction of movement along said course.

11. A radio beacon system for guiding craft along a predetermined course, comprising guiding radio beacon means arranged at spaced points along said course and aligned to provide radiation patterns overlapping along said course, successive

50 ones of said beacons operating at different radio frequencies, mobile receiver means for movement along a course in the radiation fields of said beacons, means for providing receiver triggering signals in the area of overlap of said beacon, control means responsive to said triggering signals in said mobile receiver for rendering said receiver

55 means responsive to the next successive beacon in the direction of movement of said mobile receiver along said course to assure operation of said receiver to change its condition of reception at substantially the same point, regardless of direction 60 of movement along said course.

12. A radio beacon system for guiding craft along a predetermined course, comprising guiding radio beacon means arranged at spaced points along said course and aligned to provide radiation patterns overlapping along said course, successive

ones of said beacons operating at different radio frequencies, mobile receiver means for movement along a course in the radiation fields of said beacons, control means in said mobile receiver for rendering said receiver means responsive to the beacon of predominant signal strength, marker beacon means arranged in the area of overlap of said guiding beacons, and means for applying energy of the frequency of the next preceding guiding beacon to said marker beacon to provide sharp change in signal strength in a given area to assure operation of said control means to change the condition of receiver reception in said given area, regardless of direction of movement along said course.

13. A radio beacon system for guiding craft along a predetermined course, comprising unidirectional guiding radio beacon means arranged at spaced points along said course and aligned so that the radiation patterns overlap along said course, successive ones of said beacons operating at different radio frequencies, mobile receiver means for movement along a course in the radiation fields of said beacons, control means in said mobile receiver responsive to said different radio frequencies for rendering said receiver means responsive to the beacon of predominant signal strength, marker beacon means arranged in the area of overlap of said guiding beacons and means for applying energy of the frequency of the next preceding guiding beacon in the direction of the minimum of the unidirection radiation to said marker beacon to provide sharp change in signal strength in a given area to assure operation of said control means to change the condition of receiver reception in said given area, regardless of direction of movement along said course.

14. In a radio communication and guiding system for guiding craft along a predetermined course and establishing communication with said craft, wherein a plurality of unidirectional guiding beacons are aligned so that their radiation patterns overlap at points along said course in the vicinity of the succeeding beacon, the successive ones of said beacons operating at different radio frequencies, and cooperating with a mobile receiver moved along the course in the fields of radiation of said beacon, said receiving apparatus having adjustable means responsive to predetermined signals to adjust it for response to the corresponding next successive radio beacon in the direction of travel of said craft, and to communication signals transmitted from the beacon station simultaneously with and on the same radio frequencies as the corresponding guiding beacons; an arrangement for assuring adjustment of said receiver means for reception of said beacon energy and said communication signals in substantially the same areas along said course, regardless of the direction of travel of said craft, comprising marker beacon means for producing a radiation pattern transverse of said course in the area of overlap of said beacons and adjacent said beacons, and means for energizing said marker beacons with said predetermined signals to control adjustment of said adjustable means.

15. In a radio communication and guiding system for guiding craft along a predetermined course and establishing communication with said craft, wherein a plurality of unidirectional guiding beacons are aligned so that their radiation patterns overlap at points along said course in the vicinity of the succeeding beacon, the successive ones of said beacons operating at different

radio frequencies, and cooperating with a mobile receiver moved along the course in the fields of radiation of said beacon, said receiver having adjustable means to adjust it for response to the corresponding next successive radio beacon in the direction of travel of said craft, and to communication signals transmitted from the beacon station simultaneously with and on the same radio frequencies as the corresponding guiding beacons; an arrangement for assuring adjustment of said receiver for reception of said beacon energy and said communication signals in substantially the same areas along said course, regardless of the direction of travel of said craft, comprising control signal radiating means for producing a radiation pattern transverse of said course in the area of overlap of said beacons and adjacent said beacons, and control means in said receiver responsive to said radiated control signals to control adjustment of said adjustable means.

16. A system according to claim 15 wherein means is provided for transmitting the guiding beacon signals and the communication signals as different types of modulations, one of said modulations being in the form of amplitude modulation, and the other modulation being in the form of modulated pulses of short duration and of a high amplitude relative to the amplitude of said amplitude modulations, further comprising means in said receiver for segregating said amplitude and said pulse modulations.

17. A system according to claim 15 wherein means is provided for transmitting the guiding beacon signals and the communication signals as different types of modulations, one of said modulations being in the form of amplitude modulation, and the other modulation being in the form of modulated pulses of short duration and of a high amplitude relative to the amplitude of said amplitude modulations, further comprising segregating means in said receiver for limiting received energy to a value not greater than twice the average carrier energy level, filter means in the output of said segregating means for separating out the amplitude modulated signals, clipper means for clipping the energy above said limiting level for separating out said pulses, and means for demodulating said pulses to derive the modulation envelope thereof.

18. A system according to claim 15, further comprising means at said mobile receiver and mobile therewith for transmitting a series of triggering signals, and means at each said beacon station responsive to said triggering signals for rendering said beacon stations operative to transmit beacon signals.

19. A system according to claim 15, further comprising normally open switch means at said beacon stations normally rendering said beacon and said communication transmission inoperative, transmitter means mobile with said mobile receiver for transmitting a series of triggering signals, and means at said beacon stations responsive to said triggering signals for closing said switch means.

20. A system according to claim 15, further comprising communication means for transmitting a plurality of channels for communications from each station and segregating means in said receiver for reproducing a selected one of said channels.

21. A system according to claim 15, further comprising communication transmitting means on said craft and communication receiver means at each of said stations for receiving communica-

tion signals from said communication transmitting means.

22. In a radio communication and guiding system for guiding craft along a predetermined course and establishing communication with said craft, wherein a plurality of unidirectional guiding beacons are aligned so that their radiation patterns overlap at points along said course in the vicinity of the succeeding beacon, the successive ones of said beacons operating at different radio frequencies, and cooperating with a mobile receiver moved along the course in the fields of radiation of said beacon, said receiver having adjustable means responsive to adjust it for response to the corresponding radio beacon, and to communication signals transmitted from the beacon station simultaneously with and on the same radio frequencies as the corresponding guiding beacons; an arrangement for assuring adjustment of said receiver for reception of said beacon energy and said communication signals in substantially the same areas along said course, regardless of the direction of travel of said craft comprising, marker beacon means for producing a radiation pattern transverse of said course in the area of overlap of said beacons and adjacent said beacons, and means for energizing said marker beacons at a frequency differing from that of the adjacent beacon and corresponding to the frequency of the other overlapping beacon field.

23. A radio communication and guiding system for guiding craft along a predetermined course and establishing communication with said craft, comprising a terminal communication system, a plurality of repeater stations arranged along said course, means for transmitting communication channels from said terminal system for repetition by said repeater stations, alternate ones of said repeaters operating at different carrier frequencies, unidirectional guiding beacons arranged at each of said repeater stations for transmitting guiding signals overlapping the next succeeding repeater station, said guiding beacon signals having alternately different frequencies corresponding to the frequencies of said communication signals, radio marker beacons arranged at each repeater station for transmitting marker beacon signals transversely of said predetermined course and in the zone of overlap of said beacon signals, means for energizing said marker beacon with different signals operatively related to the next preceding communication signal.

24. A radio communication and guiding system for guiding craft along a predetermined course and establishing communication with said craft comprising, a terminal communication system, a plurality of repeater stations arranged along said course, means for transmitting communication channels from said terminal system for repetition by said repeater stations, alternate ones of said repeaters operating at different carrier frequencies, unidirectional guiding beacons arranged at each of said repeater stations for transmitting guiding signals overlapping the next succeeding repeater station, said guiding beacon signals having alternately different frequencies corresponding to the frequencies of said communication signals, radio marker beacons arranged at each repeater station for transmitting marker beacon signals transversely of said predetermined course and in the zone of overlap of said beacon signals, and means for energizing said marker beacon at a carrier frequency cor-

responding to the next preceding communication signal.

25. A radio communication and guiding system for guiding craft along a predetermined course and establishing communication with said craft comprising a terminal communication system, a plurality of repeater stations arranged along said course, means for transmitting communication signals from said terminal system for repetition by said repeater stations, alternate ones of said repeaters operating at different carrier frequencies, unidirectional guiding beacons arranged at each of said repeater stations for transmitting guiding signals overlapping the next succeeding repeater station, said guiding beacon signals having alternately different frequencies corresponding to the frequencies of said communication signals, radio receiving apparatus aboard each said craft for receiving said communication signals and said beacon signals and means in the output of said radio receiving apparatus for segregating said beacon signals and said communication signals.

26. In a multiplex radio communication system for communicating between a base station and a mobile station through a radio repeater unit, a system for simultaneously producing a guiding indication for said mobile station, comprising guiding signal radiation means at said repeater unit, means at one of said stations for transmitting control signals, and means at said repeater unit responsive to said control signals for controlling operation of said guiding signal radiation means.

27. In a multiplex radio communication system, a base station, a plurality of repeaters forming a repeater chain cooperating with said base station, a mobile station means for establishing a communication between said base station and said mobile station over at least one of said repeaters, means at one of said stations for transmitting control signals, guiding signal radiation means located at a plurality of said repeaters and control means cooperating with each of said guiding signal radiation means and responsive to said signals for operating said guiding signal radiation means.

28. A communication system according to claim 27 wherein said means responsive to signals comprises means to operate selectively a desired one of said guiding signal radiation means.

29. A system for guiding a mobile unit along a predetermined route, comprising a base station, a plurality of repeater units arranged along said route for repeating control signals from said base station, guide signal transmission means at said repeater units and means responsive to said control signals for operating said guide signal transmission means to produce a guiding indication radiation along said route.

30. In a multiplex communication system in which signals may be transmitted over multiplex channels between a base station and a mobile unit over a plurality of repeater units arranged along a given line, a system for simultaneously guiding said unit along the course defined by said line, comprising separate radio guiding signal radiation means located at respective ones of said repeater stations, control means for each of said guiding signal radiation means, and means on said mobile unit for transmitting control signals to said control means for controlling operation of said radio guiding signal radiation means, whereby the radio guiding signal radiation means within the radiation field of the equipment on

said mobile unit will be energized to provide a course indication.

31. A communication system according to claim 30 wherein said guiding system comprises a directive antenna means, means for energizing said directive antenna means to produce substantially overlapping guiding indications along said course line, and means for energizing said directive radiating means with other energy in a different relationship to provide a communication channel between said antenna means and said mobile unit.

32. In a communication system wherein communication between a base station and a mobile unit is established over a series of repeater stations arranged in a line, a system for guiding said unit along said line, comprising radio guiding means at said repeater stations for producing a radio guiding radiation pattern, said guiding means being positioned to provide a guiding course along said line, and means at said repeater stations responsive to signals from said base station for energizing said guiding means.

33. In a communication system wherein communication between a base station and a mobile unit is established over a series of repeater stations arranged in a line, a system for guiding said unit along said line, comprising radio guiding means at said repeater stations for producing a radio guiding radiation pattern, said guiding means being positioned to provide a guiding course along said line, means at said repeater stations responsive to signals from said base station for energizing said guiding means, means at said mobile unit for transmitting control signals, and means at the repeater stations responsive to said transmitted control signals for energizing said guiding means.

34. A receiver for receiving and segregating two sets of signals, one of said sets of signals comprising amplitude modulation waves and the other set of signals comprising pulses of high amplitude with respect to the amplitude modulated waves, comprising means for receiving both said signals, means for dividing the energy of the received signals for application to two branches, means for limiting said received energy in one branch to substantially twice the average amplitude of the energy of one set of signals, means for filtering said limited energy to derive said one set of signals, means for threshold clipping said received energy in the other branch at a level above said average energy level of said one set of signals to separate out said pulses, and means for demodulating said pulses to derive said other set of signals therefrom.

35. A multiplex and guiding system for trans-

mitting intelligence signals to a craft simultaneously with guiding signals on a common radio frequency, comprising means for transmitting one set of signals as amplitude modulation, transmitting the other set of signals as pulses of high amplitude with respect to said transmitting signals first mentioned, means for receiving both sets of signals on said craft, means for dividing the energy of said received signals for application to two branches, means for limiting said received energy in one branch to substantially twice the average amplitude of the energy of said one set of signals, means for filtering said limited energy to derive one set of signals, means for threshold clipping said received energy in the other branch at a level above twice said average energy level of said one set of signals to separate out said pulses, and means for demodulating said pulses to derive said other set of signals therefrom.

36. In a communication system wherein communication between a base station and a mobile unit is established over a series of repeater stations arranged in a line, a system for guiding said unit along said line, comprising radio guiding means at said repeater stations for producing a radio guiding radiation pattern, means for characterizing said guiding radiation by relatively low level amplitude modulation signals, said guiding means being positioned to provide a guiding course along said line, and means for transmitting signals for communication with said unit in the form of modulated pulses of energy at an amplitude level at least greater than the highest amplitude of said guiding modulation signals.

37. A system according to claim 36, further comprising receiver means for receiving said guiding and communication signals, segregating means in said receiver for limiting received energy to a value not greater than twice the average amplitude level of the guiding modulation signal, filter means for separating out the amplitude modulated signals, clipper means for clipping the energy above said limiting level for separating out said pulses, and means for demodulating said pulses to derive the modulation envelope thereof.
